UNITED STATES PATENT OFFICE.

OSCAR W. LUNDEEN, OF OAKLAND, NEBRASKA.

SPIITTOON-WASHING MACHINE.

1,092,924.

Specification of Letters Patent. Patented Apr. 14, 1914.

Application filed August 19, 1912. Serial No. 715,896.

To all whom it may concern:

Be it known that I, OSCAR W. LUNDEEN, a citizen of the United States, residing at Oakland, in the county of Burt, State of Nebraska, have invented certain new and useful Improvements in Spittoon - Washing Machines; and I do hereby declare the following to be a full, clear, and exact description of the invention, such as will enable others skilled in the art to which it appertains to make and use the same.

This invention relates to new and useful improvements in cuspidor cleaners.

The object of the invention is to simplify the general structure and improve the efficiency and ease of operation of devices of this character.

A further object resides in the provision in a device of this character, where the cuspidor is rotatable on a spindle, of means for swinging the cuspidor upon the spindle.

With the above objects in view, the invention consists of certain novel details of construction and combinations of parts hereinabove fully described and claimed, it being understood that various modifications may be made in the minor details of construction within the scope of the appended claims.

In the accompanying drawings, forming part of this specification, Figure 1 is a side elevation of the device. Fig. 2 is a plan view of the device. Fig. 3 is a longitudinal sectional view through the device. Fig. 4 is a cross sectional view taken on the line 4—4 35 Fig. 3. Fig. 5 is a horizontal sectional view taken on the line 5—5 Fig. 3. Fig. 6 is a fragmentary sectional view showing the means of centering the cuspidor on the mandrel. Fig. 7 is a cross sectional view 40 taken on the line 7—7 Fig. 3. Fig. 8 is a detail perspective view of the tongs.

Referring now to the drawings in which like characters of reference designate similar parts, 10 designates a casing of the general shape shown in Fig. 2, the casing being supported upon legs 11, and being equipped with a hinged cover 12. A water supply pipe 13 enters the casing and extends along the bottom 14 thereof, the pipe being 50 equipped with two upright branches 15 and 16 which are closed by caps 17 and 18 and are equipped near the tops with outlet openings 19 and 20.

The inverted cuspidor 21 is designed to be 55 supported upon the branch 16, and to attain this end a tri-forked spindle 22 is rotatively

mounted in the cap 20 of the branch, as shown at 23, the branches of the spindle engaging with the bottom of the cuspidor, as shown in Figs. 3 and 4.

For centering the cuspidor on the spindle 22, a lever 24 is provided with an upturned gudgeon 25, which journals for rotation in strap bearings 26 carried on the inner face of the casing, there being a handle 27 secured to the upper end of the gudgeon and extending horizontally therefrom to swing the lever 24 in a horizontal plane. The cuspidor is rotated continuously as will presently be described, and during such rotation should the cuspidor not be truly centered on the spindle, the cuspidor will tend to tilt upon the spindle. By manually swinging the lever 24 into the path of movement of the tilted cuspidor, the lever serves to press down upon the high side of the cuspidor with a resultant forcing of the cuspidor to assume a horizontal position and become centered upon the spindle.

For rotating the cuspidor continuously, a mandrel is employed, the mandrel comprising a stub shaft 28 which is journaled for rotation in an opening formed in the cover 12 and is equipped with a sliding sleeve 29, which terminates in a rubber tip 30 which bears upon the cuspidor bottom, the sleeve being normally frictionally held against the cuspidor bottom by means of a helical spring 31 which is confined between a collar 32 carried by the shaft and a collar 33 carried by the sleeve. The shaft is equipped at the upper end with a bevel pinion 34 which meshes with a bevel pinion 35 carried by a shaft 36 which is journaled for rotation in bearings 37 carried on the hinged cover 12 and terminates in a crank handle 38. By rotating the handle the sleeve is rotated with a resultant rotation of the cuspidor.

The streams from the outlet openings 19 of the branch 15 flare upon the exterior of the cuspidor and the streams from the outlet openings 20 of the branch 16 play upon the inner surface of the cuspidor, with a resultant cleaning of the cuspidor exteriorly and interiorly during rotation of the cuspidor. For scouring the exterior of the cuspidor, a vertically disposed scouring brush 39 is mounted to frictionally bear upon the cuspidor, and to attain this end a lever 40 is journaled at the upper end between 110 hinges 41 carried on a stationary closure 42 of the casing top, the lever being equipped

at the lower end with clamps 43 which engage the brush back, and further being equipped at the upper ends with a connecting link 44 which is terminally connected 5 to a rocking lever 45 carried on said stationary closure. By forcing the lever outwardly, the brush is rocked into snug engagement with the outer wall of the cuspidor.

- 10 For scouring the inner surface of the cuspidor mouth, a substantially conical brush 46 is mounted on the branch 16 of the water pipe, this brush being urged upwardly into snug engagement with the cuspidor mouth 15 by means of a lever 47 which is pivoted on a post 48 carried by the water pipe, the lever being equipped at the outer end with a weight 49, the latter being of sufficient weight to counterbalance the conical brush 20 and urge the latter upwardly into snug engagement with the cuspidor mouth.

In Fig. 8 is shown a pair of tongs 50, which may be employed in removing and inserting the cuspidor upon the spindle after 25 the hinged cover has been opened to permit of insertion of the cuspidor within the casting.

What is claimed is:

- 30 1. In a cuspidor cleaning device, a spindle adapted to enter and support an inverted cuspidor, means for rotating said cuspidor on said spindle, a laterally disposed vertically extending brush adapted to engage one side of said cuspidor, and a horizontally 35 swinging lever adapted to engage the bottom of said cuspidor opposite from said

brush and center the cuspidor upon said spindle.

2. In a cuspidor cleaning device, an upright water supply pipe, a spindle turnably 40 mounted on the top of said pipe, and adapted to enter and support an inverted cuspidor, means for rotating said cuspidor on said pipe, a laterally disposed and vertically extending brush adapted to engage with one 45 side of said cuspidor, and a horizontally disposed lever adapted to swing on a vertical pivot and engage with the bottom of said cuspidor opposite from said brush whereby to center said cuspidor on said spindle. 50

3. In a cuspidor cleaning device, an upright water supply pipe, a spindle rotatably mounted on the top of said pipe and adapted to enter and support an inverted cuspidor, a conical brush on said pipe adapted to enter 55 the mouth of said cuspidor, a laterally disposed brush adapted to engage and conform to the contour of one side of said cuspidor, and a lever adapted to swing in a horizontal plane and to engage with the bottom of said 60 cuspidor to one side of the center thereof diametrically opposite from the last named brush and depress the high side of said bottom during rotation of said cuspidor whereby to center said cuspidor on said spindle. 65

In testimony whereof, I affix my signature, in presence of two witnesses.

OSCAR W. LUNDEEN.
